UNITED STATES PATENT OFFICE.

WILLIAM G. ZEIGLER, OF CHICAGO, ILLINOIS.

CONNECTING-ROD.

1,273,712.

Specification of Letters Patent. Patented July 23, 1918.

Application filed August 17, 1917. Serial No. 186,754.

To all whom it may concern:

Be it known that I, WILLIAM GEORGE ZEIGLER, a citizen of the United States, residing at Chicago, in the county of Cook and State of Illinois, have invented new and useful Improvements in Connecting-Rods, of which the following is a specification.

This invention relates to machine elements, and more especially it is a connecting rod or pitman made of sheet metal, preferably vanadium steel.

One object of the invention is the production of such a pitman from a strip of steel by the simplest possible means so as to save time. Another object is to provide a finished article of this character which, while very light in weight, possesses great strength. A third object is to avoid buckling which so often occurs in devices of this character at points adjacent the eyes. A fourth object is to do away with castings and to eliminate machining and final treatment as far as possible.

With these and other objects in view, I give the details of my preferred construction of this pitman or connecting rod below, and make reference to the accompanying drawings wherein—

Figure 1 is a plan view of this improved pitman, one oil hole being shown and one bushing in place.

Fig. 2 is a plan view of the blank from which the pitman is made, the full inner lines outlining holes and openings and the dotted lines indicating the lines on which the blank is to be bent or folded.

Fig. 3 is a perspective detail in section showing the first step of my method of making this pitman, which consists in folding the blank on the longitudinally dotted lines.

Fig. 4 is a detail showing the second step which consists in bending the blank at its center to form an eye; and Fig. 5 is a side elevation of the other end of the pitman and illustrative of the results of the third step which consists in bending the blank on the transversely dotted line into quadrants.

Fig. 6 is a cross section on the line 6—6 of Fig. 4.

Figs. 7 and 8 are details of modifications or amplifications.

The blank 1 shown in Fig. 2 is substantially rectangular and approximately twice the length it is desired the finished article should have. It is by preference composed of pressed vanadium steel about one-eighth

of an inch in thickness and nearly two inches in width, and its length is dependent on the use to which the pitman is to be applied although I have found this invention to work well on the connecting rods of automobile engines. According to the size of the engine, the suggested proportions may be varied. The dotted lines 2 and 3 on the blank in Fig. 2 indicate where it is to be bent at right angles as seen in Fig. 3 to produce two side leaves 4 and 5, between which is an upstanding rib 6 which of course necessitates that the metal shall be folded on itself along the dotted line 7, and as the leaves are of equal width the fold line 7 will of course be along the transverse center of the strip. Recognizing the difficulties which attend bending metal of angular cross section, I have made provision for bending only the leaves of this strip and therefore the material within the rib is not affected by what follows—it need be neither stretched nor condensed, and it is not weakened or machined in any way. Having folded the blank on the line 7 and bent it on the lines 2 and 3, it now has the cross section illustrated in Fig. 3.

At the mid-length of the blank it is formed with an opening 10 coextensive in width with the distance between the lines 2 and 3, as long as may be necessary, according to the size of the eye to be produced (see Fig. 4), and having its sides straight but its ends cut with reentrant points, each made up of slightly curved lines 11 and 12 meeting in an angle 13 at the transverse center of the opening. Past the sides of the latter run the leaves 4 and 5 as shown by reference numerals marked thereon. The next step in the formation of this pitman consists in bending the blank at its mid-length on a transverse line intersecting the opening 10, but the bend here given is a gentle one so as to produce an eye 14 as seen in Fig. 4, and by preference the eye is formed by bending the metal (which is only the two leaves) around a mandrel to give the eye a truly cylindrical formation. Said mandrel is shown in Fig. 4 as a bushing 15, and the same may be fastened in the eye by shrinking the latter upon it or by any other improved means—it may even be fastened removably so that it may be replaced when it becomes worn, and details need not be given.

Near each end of the blank is formed an opening 20 of the same width but of less

length than the opening 10, its inner end having a reentrant point 23 formed by two curved lines 21 and 22, and its outer end 24 being cut off straight; and between said outer end and the extremity of the blank the leaves 4 and 5 are punched to produce holes 25. Another step in the formation of this pitman consists in bending each end of the blank on a transverse line intersecting the opening 20 so as to produce a curve or quadrant 26 as seen in Fig. 5, and bending the metal sharply outward on the line 27 to produce an ear 28 at the extremity of each quadrant. A clip 36 is provided having a semi-cylindrical body of a size equal to both quadrants, and ears 38 at its ends, and bolts or screws 39 are passed through holes in the contacting ears 28 and 38. If desired, thin washers or shims 34 may be interposed between these ears initially, for removal later when it is desired to reduce the size of the eye. Such shimming may be employed at this end of the pitman, but by preference I dispose a bushing 35 within the eye, like the bushing within the other eye of the pitman, and it may be held there by tightening up the screws 39 or by employing other means as suggested above.

The formation of the blank with its openings and holes will be accomplished at one stroke of the die, folding it on the line 7 and bending it on the lines 2 and 3 will next be done, bending the article to produce the quadrants 26 and the eye 14 will follow, and this brings the leaves 4 and 5 at one end of the blank into contact with those of the other end as seen in Fig. 6. At suitable points throughout the length of the device as at 40 these contacting leaves are next connected with each other by electric welding or other means which may be selected. Probably the clip 36 will be applied last, but the order followed in carrying out the steps of this operation is not important. It is quite possible to provide oil holes 41 through one or both of the eyes and their contained bushings, and if this pitman is not to be used submerged in oil or lubricated by the splash system, oil cups or grease cups may be mounted in these holes. I have shown the bushing 35 as larger than the bushing 15, and the curved lines 21 and 22 are therefore struck on a greater radius than the lines 11 and 12.

A striking feature of this invention will be found in the fact that when one end of each opening 20 and both ends of the opening 10 are formed as described, the bending or curving of the leaves 4 and 5 to form the eye 14 and the quadrants 26 automatically brings the ends of said openings into abutting contact with the outer wall of the eye as seen at 21' in Fig. 4 and the outer wall of each quadrant as seen at 11' in Fig. 5, and the parts may there be welded to-

gether when welding is done at the points 40. With the shank of the pitman having the sectional shape of a cross shown in Fig. 6, it is now obvious that the leaves are of double thickness; they stand in a horizontal plane through the axes of the eyes and bushings, and they reliably brace the extremities of the eyes or bearings against end thrusts; whereas the upright ribs (also of double thickness) abut the inner sides of the bearings at their mid-length and greatly strengthen the structure by additionally resisting end thrusts and by preventing buckling which so often occurs in a flat shank at points next the bearings. In other words, the cross-shaped section of the shank of this pitman not only increases its strength to a greater degree than its weight, but also affords a considerable surface of resistance transversely to the axis of each eye in addition to that afforded by the horizontal leaves, and all four arms of the cross are of double thickness. Finally, it will be observed that no metal of angular cross section has anywhere been bent, as all the bending in producing the eye or the quadrants occurs in the leaves only, and these are flat.

A slight modification or amplification is shown in Fig. 7 where the outer end of the endmost hole or opening 20 instead of being cut off straight as at 24 in Fig. 2 is cut off on a reentrant line 24' producing a point 23'. With this construction when the blank is folded, instead of leaving a space at each side of the quadrant 26 as shown in Fig. 5, the reentrant line and point close up against the quadrant as indicated in Fig. 8.

What is claimed is:

1. A connecting rod comprising spaced bearings, and a sheet metal shank connecting them and made up of upper and lower members whereof each consists of two leaves disposed edge to edge and secured to the leaves of the other member, and a rib of double thickness integrally connected with the inner edges of said leaves and projecting outward from their plane.

2. A connecting rod comprising spaced bearings, and a shank connecting them and made up of upper and lower members whereof each consists of a sheet metal strip folded at its transverse center to produce a rib of double thickness and bent outward from the rib into two leaves standing in a single plane, the leaves of one member being secured to those of the other and integrally united at their ends with said bearings, while the ends of said ribs abut such bearings.

3. A connecting rod composed of a strip of sheet metal having openings at its center and near its ends, the same upbent between said openings into a longitudinal rib at the transverse center of the strip leaving flat leaves along its edges at opposite sides of

the rib and extending past all openings, the leaves being bent into a complete bearing opposite the central opening and bent into a half bearing opposite the other opening the 5 ends of the ribs abutting said bearings.

4. A connecting rod composed of a strip of sheet metal having openings at its center and near its ends, both ends of the central opening and the inner ends of the other openings being formed with reëntrant points whereof each is made up of two curved lines, 10 said strip being folded along its transverse center into a longitudinal rib leaving flat

leaves at opposite sides of the rib and extending past all openings, the leaves opposite the central opening being bent into an eye and opposite the other openings into quadrants and the ends of the ribs constituted by said curved lines abutting the walls of the quadrants and eye, means for holding the leaves in contact with each other, and a complementary clip attached to said quadrants and with them making up a second eye. 15 20

In testimony whereof I affix my signature. 25
WILLIAM G. ZEIGLER.
